(57) CLAIM

The ornamental design for the clothes bagging and hanging rack, as shown and described.

DESCRIPTION

FIG. 1 is a perspective view of the clothes bagging and hanging rack showing my new design;

FIG. 2 is a reduced top view of my invention;

FIG. 3 is a reduced rear view of my invention;

FIG. 4 is a reduced front view of my invention;

FIG. 5 is a reduced side view showing the use of my invention; and,

FIG. 6 is a reduced side view of my invention.

The broken lines shown in FIG. 5 are for illustrative purposes only and forms no part of the claimed design.
